(57) **CLAIM**

The ornamental design for a worklight faceplate, as shown and described.

DESCRIPTION

FIG. 1 is a perspective view of the worklight faceplate.

FIG. 2 is a front elevational view of the invention.

FIG. 3 is a rear elevational view of the invention.

FIG. 4 is a top plan view of the invention.

FIG. 5 is a bottom plan view of the invention.

FIG. 6 is a right side view of the invention; and,

FIG. 7 is a left side view of the invention.

The broken lines shown are included for the purpose of illustrating environment and form no part of the claimed design.
